SINGLE DISK SHAFT LOCK

Skardon T. Smith, Detroit, Mich.

Application May 4, 1942, Serial No. 441,667

5 Claims. (Cl. 192—8)

This invention relates to an improvement of my former locking device set forth in Patent No. 2,028,629, dated Jan. 21, 1936, and herein provides means for applying a single lock disk for locking connected shafting within a housing.

The object of my invention is to provide a locking unit for shafting, designed to prevent backward rotation whenever an opposing force is applied through the driven unit.

Another object is to provide a simple disk shaft connector capable of functioning freely when the rotating force is applied through the driving shaft unit, but will automatically lock within a fixed housing if any rotating force is applied thereto through the driven unit section.

A further object is to provide a locking unit that can be installed within any shaft line capable of adoption to a fixedly mounted support housing unit.

These several objects are attained in the preferred form by the construction and arrangement of parts more fully hereinafter set forth.

Similar parts on all drawings are marked by similar numerals or letters.

Fig. 1 is an elevation of the assembled unit, showing the housing and means for mounting same.

Fig. 2 is an end view of the housing taken on the line 2—2 of the Fig. 1, showing the general housing formation.

Fig. 3 is a sectional view, except for the central shafting units, taken on the line 3—3 of the Fig. 2, showing the general arrangement of the operating parts.

Fig. 4 is a cross-sectional view taken on the line 4—4 of the Fig. 3 showing the relative position of the shaft contact units as applied to the internal lock disk.

Figs. 5 and 6 illustrate the detail construction of the driving shaft collar and lug.

Figs. 7 and 8 illustrate the detail construction of the driven shaft collar and lug.

Figs. 9 and 10 illustrate forms of locking disks applicable to the shaft housing, and displacement spring recesses adaptable thereto.

Fig. 11 is a modified sectional view similar to Fig. 3, but illustrated with the driven section made tubular in form and rotatably mounted over the driving shaft section, and provided with attached gears for connecting therewith inside the housing chamber.

Fig. 12 is a cross-section taken on the line 12—12 of the Fig. 11, showing the modified lug members within the lock disk recess, also illustrating displacement springs applied for cen-

tralizing the disks when otherwise unrestrained.

Fig. 13 is an exaggerated cross-sectional view as would be seen on the line 4—4 of the Fig. 3 showing the disk 8 and contacting operating lug k of the driven shaft 10 when actually displacing the disk 8 to its locking position.

The general construction of my device, comprises a fixedly mounted shaft housing formed with a cylindrical chamber positioned concentric with the end shaft bearings, centrally therebetween, a locking disk rotatably mounted within the housing chamber and provided with means for operatively connecting same with separated shaft sections as may be mounted within the 15 housing end bearings.

I will now describe more fully the detailed construction of my device, referring to the drawings and the marks thereon.

The housing A is preferably formed of a cylindrical brake ring 1 having turned cylindrical end bearing caps 2 and 3 rigidly mounted thereon by suitable stud bolts 4. The brake ring 1 is a turned cylindrical section, preferably with a hardened and ground inner brake surface a. Both end bearing caps 2 and 3 are likewise turned cylindrical sections, and are preferably provided with roller bearings 5, designed and positioned concentric with the housing chamber B. The bearing cap 3 is formed with a flat end surface b positioned at right angles to the shaft axis, and is provided with suitable anchor bolt holes 7 for securely attaching the housing A to any suitable support C. Within the housing brake ring 1 is fitted a semi-cylindrical locking disk 8 of a diameter slightly smaller than the receiving ring surface a, allowing a slight edgewise displacement therein transversely of the shaft axis. The lower edge c of the lock disk 8 is cut away along an arc less than a semi-circle, forming opposing contact points d on opposite disk edges, designed and positioned to contact the brake ring surface a at a pre-determined locking angle whenever said lock disk is so displaced within the housing chamber by an eccentrically applied force. A driving shaft 9 is rotatably mounted through the end bearing cap 2, and a driven shaft 10 likewise is rotatably mounted through the opposite end bearing cap 3, as illustrated in the Fig. 3 of the drawings. Each shaft section 9 and 10 is provided with a collar section e and f respectively, for retaining the shafts in position within the housing chamber. The driving shaft collar e is provided with an elongated beveled lug g across its inner face, designed to fit and engage the edge h of the disk recess D, for retaining the locking disk 8 in

a free turning position concentric with the inclosing brake ring surface *a* whenever a turning force is applied thereto through the driving shaft *9* causing the lug edge to contact the disk recess edge *h* and force said disk sidewise transversely of the shaft axis and in a concentric position with the inclosing chamber *B*. Likewise the driven shaft collar *f* is provided with a similar shaped lug *k* across its inner face, oppositely disposed and designed to engage the edge *m* of the disk recess *D* for forcibly displacing the disk *8* in like manner but in the opposite direction within the chamber and securely locking same with the brake ring walls whenever a counter-turning force is applied thereto through the driven shaft *10*. The disk recess *D* provides a rigid yoke for securely clamping the adjoining lugs *g* and *k* together, uniting the shaft sections for continuous rotation whenever the lock disk *8* is free to rotate within the housing. If desired, a stressed displacement spring *15* may be inserted in either side disk recess, *16* or *17*, for retaining the lock disk *8* under a predetermined pressure in its centralized, or locking position, when otherwise unrestrained, thus controlling the disk operation for moderately light resisting forces.

It can readily be seen that any turning force that is applied to the lock disk *8* through the driving shaft section *9* will centralize the disk within the housing chamber and retain same in its free turning position therein allowing both disk and connected shaft *10* to rotate freely within the housing *A*. However, if any opposing force be applied to the disk *8* through the driven shaft *10*, the lock disk *8* will be automatically displaced transversely of the shaft axis within the housing chamber, rigidly locking with the chamber walls *a* and stop all further shaft rotations. The weakened sections *x* of the lock disk *8* as formed by the elongated disk recess *D*, provides ample means for slight disk distortion when placed under an excessive overload, allowing a disk slippage to prevent breakage of the units when so overloaded.

The Figs. 11 and 12 illustrate a modified form of the same device, showing the driving shaft *9a* extended through both housing bearings, and the driven unit *10a* formed of a tubular section geared at one end, and rotatably mounted over the driving section within the housing chamber *B*. The driven geared unit *10a* is provided with an external connecting idler gear *20* rotatably mounted within the housing walls, showing one means of connecting the operating mechanism with an external driven unit. The shaft sections *9a* and *10a* are provided with operating sections *ga* and *ka* respectively and engage the lock disk recess walls *h* and *m* as in the former case. The application and operation are exactly the same as in the former case.

Having fully described my single disk shaft lock, what I claim as my invention and desire to secure by Letters Patent is:

1. A disk shaft lock for preventing backward rotation of a connected driven section, comprising a rigidly mounted housing formed with a centrally positioned cylindrical chamber provided with connected shaft bearings through opposite ends thereof positioned concentric with the cylindrical housing chamber axis, a driving shaft section and a driven section, each formed with projected end operating lugs rotatably mounted within the housing and bearings and positioned with their respective lugs adjacent each other within the housing chamber, a lock disk formed

with a central parallel wall recess rotatably mounted within the housing chamber capable of locking with the chamber walls by forcible displacement transversely of the shaft axis, said disk recess being designed and positioned to fit over and engage both driving and driven operating lugs in a manner to be displaced thereby to release or lock said disk with the chamber walls when a rotating force is applied thereto through the respective corresponding operating lugs.

2. A disk shaft lock adapted for preventing backward rotation of a connected driven section, comprising a rigidly mounted housing formed with a centrally positioned cylindrical chamber provided with connected shaft bearings through opposite ends thereof positioned concentric with the chamber axis, a driving shaft rotatably mounted within one housing bearing and a driven section, rotatably mounted within the opposite end bearing, each shaft formed with projected operating lugs on the inner end thereof positioned within the chamber recess, oppositely disposed to each other, a lock disk designed to lock with the chamber walls when forcibly displaced therein transversely of the shaft axis, rotatably mounted within the housing chamber, said lock disk being formed with a central recess having oppositely parallel sides designed and positioned to fit over and engage said operating lugs, to be displaced thereby for releasing or locking said disk with the chamber walls as a rotating force is applied thereto through the respective corresponding operating lugs.

3. A disk shaft lock adapted for preventing backward rotation of a connected shaft section, comprising a rigidly mounted housing section formed with a central cylindrical chamber provided with connected shaft bearings through opposite ends thereof positioned concentric with the chamber axis, a driving shaft and a driven shaft rotatably mounted within opposite housing end bearings, each shaft inner end being formed with a projected triangular shaped operating lug designed with one outer flattened surface parallel to the shaft axis, each projected within the chamber recess and overlapping each other, a lock disk formed with one receded edge designed to engage the chamber walls at a locking angle, also formed with a parallel walled central recess, and rotatably mounted within the housing chamber capable of locking therewith when forcibly displaced transversely of the shaft axis, said lock disk central recess being designed and positioned to fit over and engage both of said triangular operating lugs along their opposite parallel sides capable of sidewise displacement thereby transversely of the shaft axis when pressure is applied to said disk recess through either of the shaft sections for respectively releasing or locking said lock disk with the housing chamber walls.

4. A single disk shaft lock adapted for preventing backward rotation of a connected driven section, comprising a rigidly mounted housing section formed with a centrally positioned chamber provided with connected shaft bearings leading through opposite ends thereof concentric with the chamber axis, a driving shaft section and a driven section rotatably mounted thereon all rotatably mounted within the housing bearings, said driving and driven sections being provided with projected operating lugs positioned within the chamber and parallel to the axis and overlapping each other, a lock disk formed with one receded edge and a parallel wall central recess rotatably mounted within the housing chamber, said disk

being designed to engage the chamber walls at a locking angle and lock therewith when under pressure applied transversely of the shaft axis, also said central recess being designed and positioned to fit over and engage both sets of operating lugs in a manner capable of a sidewise displacement thereby transversely of the shaft axis from applied pressure through either the driving or driven operating lugs, for respectively releasing or locking said lock disk with the housing chamber walls.

5. A disk shaft lock for preventing backward rotation of a connected driven section, comprising a rigidly mounted housing formed with a central cylindrical chamber provided with connected shaft bearings through opposite ends thereof positioned concentric with the chamber axis, a driving shaft section and a driven section each formed with projected operating lugs rotatably

mounted within the housing bearings positioned with their respective lugs adjacent each other within the housing chamber, a lock disk formed with a parallel wall central recess rotatably 5 mounted within the housing chamber capable of locking with the chamber walls by displacement under pressure applied transversely of the shaft axis, said disk central recess being designed and positioned to fit over and engage both driving 10 and driven operating lugs in a manner to be displaced thereby to release or lock said disk with the chamber recess walls when a rotating force is applied thereto through the respective corresponding operating lugs, and spring means 15 mounted between said lock disk and one operating lug for retaining said disk under pressure in a predetermined position within the housing chamber when otherwise unrestrained.
